UNITED STATES PATENT OFFICE.

BESTER R. WEBSTER, OF PASADENA, CALIFORNIA, ASSIGNOR, BY MESNE ASSIGNMENTS, TO WAHL ADDING MACHINE COMPANY, OF WILMINGTON, DELAWARE, A CORPORATION OF DELAWARE.

TABULATING-MACHINE.

1,118,978.

Specification of Letters Patent.

Patented Dec. 1, 1914.

Continuation in part of application Serial No. 564,795, filed June 3, 1910. This application filed September 7, 1911. Serial No. 648,185.

To all whom it may concern:

Be it known that I, BESTER R. WEBSTER, a citizen of the United States, residing at Pasadena, in the county of Los Angeles and 5 State of California, have invented a certain new and useful Improvement in Tabulating-Machines, of which the following is a specification.

This application is a continuation in part 10 of my application Serial Number 564,795, filed June 3, 1910.

My invention relates to tabulating machines, and is intended particularly for the easier listing of numbers.

15 The invention is illustrated by the drawings accompanying this specification.

Of these, Figure 1 shows an end elevation of a typewriter of the Remington visible style, and Fig. 2 shows a front elevation of 20 the same.

Mounted upon the framework 1 of the typewriter is the carriage 2. This contains the platen 3 upon which the paper is mounted as usual, and fed upward by means of 25 the ordinary paper feed lever 4. Mounted upon the back of the carriage is a tabulator bar 5 upon which may be mounted one or more tabulator stops 6. These stops are intended to coöperate with the tabulator rods 7 which are operated by the links 10, each 30 connected at its one end to a tabulator rod 7 and at its other end to one of a series of bell-crank levers 9. Coöoperating with these levers are a set of rods 42, each of them provided at its front end with a finger piece 40, 35 whereby it may be easily manipulated, and supplied with a collar 41 fastened thereto, and coöoperating with the levers mentioned above. Of course, the machine includes 40 keys, type levers, type bars, and other mechanisms, but as they form no part of my invention, and as their presence in the drawings would tend to confuse rather than elucidate, they have been left out.

45 Fastened to the carriage 2 of the typewriter is a typewriter rack 50 pivotally mounted upon studs 52. This rack coöperates with the escapement gear 53, as is usual. In its normal position on the typewriter, the 50 rack 50 is in mesh with the escapement gear 53 which escapement gear therefore prevents the rack and carriage attached thereto from advancing to the left. But in the operation

of the tabulator, it is necessary that the carriage should advance to the left without any 55 interference from the escapement, and this is accomplished by disconnecting it from the escapement gear 53. This is accomplished through the intermediation of a bar 60 mounted in front of all of the tabulator 60 rods 7 and supported at its ends by two side pieces 61 pivotally mounted upon studs 62 in the framework. From one of the side pieces 61 there extends an arm 63 which rests upon an arm 64 of lever 65, pivotally 65 supported at its fulcrum 66 and having another arm 67 bearing under the rack 50 before mentioned.

The operation of any of the tabulator finger pieces 40 and the consequent protrusion of the connected tabulator rod 7 therefore results in the swinging of the bar 60 about the studs 62, and the consequent rotation of lever 65, and the lifting up of the rack 50. The rack 50 is thus lifted away 75 and disconnected from the escapement gear 53, and the carriage is thus free to move in either direction without any interference from the escapement. Normally the carriage has a tendency to move to the left 80 which tendency is imparted to it by the tension spring drum pulley and strap as is usual.

In the drawings, 70 represents the spring 85 pulley and 71 the strap. This strap is connected to an extension 72 fastened to the carriage of the typewriter. So far, all the mechanism that has been described is old, and differs in no way from that which is on the market at present, and therefore will not 90 be further entered into here. The new features of my invention will now be taken up.

Mounted upon the framework, are another set of retracting tabulator keys 8, each provided at its upper end with finger pieces. 95 Coöoperating with each retracting tabulator key 8 is an arm 31, and all of these arms are rigidly fastened to a shaft 30 pivotally mounted in the framework. Fastened at one end to the shaft 30 and at its other end to the framework of the machine is a spring 35 which tends to hold the arms 31 in an elevated position. At one end of shaft 30 is rigidly fastened an arm 32 which is connected to one end of a link 33 whose other 100 end is connected to a three-way stop cock 24

at one end of cylinder 20. This cylinder is fastened upon the framework, and its cock is connected by a tube not shown in the illustration to a compressed air reservoir. Sliding in the cylinder 20 is a piston 21 which has extending therefrom a rod 22 connected at its other end to an arm 23 which is rigidly fastened to the paper feed lever 4 above mentioned.

- 10 The depressing of any of the retracting keys 8 results in the depressing of the co-operating arm 31, and the consequent rotating of shaft 30 against the force of spring 35, and the opening of the three-way cock 24 to the compressed air reservoir. The air therefore enters the cylinder 20 and pushes upon the piston 21 and consequently operates the paper feed lever 4. This results first in the feeding of the paper and second 20 in the retracting of the carriage. The carriage therefore is forced back to the right against the force of the tension spring and it moves to the right until it is stopped by a mechanism which will now be described.
- 25 Projecting from each of the tabulator keys 8 is a lug 11 resting upon the upper arm of the bell-crank lever 9 before mentioned. The depressing of the tabulator key therefore results not only in the retracting of 30 the carriage to the right, but also in the protruding of the tabulator rod 7 in the path of the tabulator stop 6. The carriage therefore moves to the right under the influence of the compressed air as far as it 35 can, namely, until the tabulator stop 6 strikes the protruding tabulator rod 7 where the carriage necessarily comes to rest. As long as the operator retains his finger upon the retracting tabulator key 8, the carriage 40 remains with its tabulator stop 6 pressing against the protruding tabulator rod 7. But as soon as the operator removes his finger from the retracting tabulator key 8, it rises under the influence of its spring 45 12. This removes the pressure from the co-operating arm 31 and the shaft 30 under the influence of its spring 35 therefore rotates and closes the three-way valve 24 to the compressed air reservoir, and simultaneously 50 opens the inside of the cylinder 20 to the outside air. The compressed air pressure inside of the cylinder is therefore released. Simultaneously the pressure has been released from the tabulator rod 7, which is 55 therefore retracted and removed out of the way of the stop 6. It will therefore be seen that by means of this mechanism the operator has at his command two sets of tabulator keys, the advancing tabulator keys 40, the 60 operation of which advances the carriage to the left, and the retracting tabulator keys 8 the operation of which retracts the carriage to the right. Advancing tabulator keys have been on the market for a long time.

They are employed to a great extent for the listing of numbers in a horizontal line. The retracting tabulator keys 8 find one of their uses in the listing of numbers arranged in a vertical column underneath each other. The operation is as follows. After the units figure of a number has been typewritten, the operator depresses the retracting tabulator key 8 corresponding to the highest decimal place of the next number. The carriage is therefore retracted and brought to a position corresponding to said decimal place. Simultaneously the paper is fed upward. The various places of the new number are now typewritten. After the printing of the units figure of this new number 80 the retracting tabulator key of the highest decimal place corresponding to the next number is operated, etc.

Having thus described my invention, I claim:

1. In a tabulating machine, the combination of a carriage, means for moving the carriage to the right, means for moving the carriage to the left, stopping means whereby the carriage may be located in a predetermined position in its motion, and two sets of tabulator keys, one set for governing the stopping means and means for moving carriage to the right, and the other set for governing the stopping means and means 95 for moving the carriage to the left.

2. In a tabulating machine: mechanism for advancing the carriage; mechanism for returning the carriage; means for stopping the carriage at a predetermined place; a set 100 of advancing tabulating keys, each of which controls the operation of both the carriage advancing mechanism and carriage stopping means; and another set of returning tabulating keys, controlling the operation 105 of both the carriage returning mechanism and the carriage stopping means.

3. In a tabulating machine, a carriage, a tabulator bar, one or more tabulator stops mounted upon said tabulator bar, a series 110 of tabulator rods, means for moving the carriage to the left, means for returning the carriage to the right, a set of keys co-operating with the tabulator rods and with the carriage moving means, and another set of 115 keys co-operating with the tabulator rods and the carriage returning means.

4. In a tabulating machine: a carriage; mechanism for advancing the carriage; mechanism for returning the carriage; a 120 stop member upon the carriage; a series of tabulating rods, each of them operative to stop the carriage at a predetermined place by contact with said stop member; a first series of tabulating keys co-operating with the tabulating rods; a second series of tabulating keys also co-operating with the tabulating rods; a bar operated by each of said 125

second series of tabulating keys; and a connection between the bar and the carriage returning mechanism whereby the operation of any of the second series of tabulating keys sets the carriage returning mechanism into operation and also causes its particular tabulating rod to stop the carriage at its predetermined place.

5. In a tabulating machine, a carriage 10 normally tending to move to the left, a mechanism to return it to the right, a series of tabulator rods each of which is operative to release said carriage to permit its movement and then to stop it at a predetermined 15 place, keys for operating the tabulator rods, and a second set of tabulator keys operative upon said tabulator rods and also upon the carriage returning mechanism.

6. In a tabulating machine, mechanism 20 for advancing the carriage, a set of keys operative upon the carriage initially to release it to advance, and finally to stop it at a place dependent upon the particular key of said set actuated, and a second set of keys 25 operative upon the carriage initially to return it and finally to stop it at a place dependent upon the particular key actuated.

7. In a tabulating machine, a carriage, a tabulator bar mounted upon said carriage, a tabulator stop mounted upon said tabulator bar, 30 a series of tabulator rods, the operation of any of which releases the carriage and then stops it by contacting with the tabulator stop, pneumatic means for returning the carriage to the right, a returning bar operating said pneumatic means, a series of tabulator keys each of which is operative upon one of said tabulator rods, but not operative upon the returning bar, and another 35 set of tabulator keys each of which is operative upon both a tabulator rod and the returning bar.

8. In a tabulating machine, a carriage, a tabulator stop coöoperating with said carriage, a series of tabulator rods coöoperating with said tabulator stop, the operation of any of said tabulator rods permitting the carriage to move to the left and to be located at a predetermined point, a returning 50 bar operating to return the carriage to the right, a set of tabulator keys, each of which operates its coöoperating tabulator rod but not the returning bar, and another set of tabulator keys each of which operates both 55 its tabulator rod and the returning bar.

9. In a tabulating machine, a carriage, means for moving the carriage to the left, a cylinder for air, a piston operable by the air to return the carriage to the right, a 60 stop cock governing the admission of the air into the cylinder, tabulating means for releasing the carriage to permit its motion and for stopping it at a predetermined point, a set of keys operating the tabulating 65 means but not operating the cock, and an-

other set of tabulator keys operating both the tabulating means and the cock.

10. In a tabulating machine, a carriage, means for moving the carriage to the left, a cylinder for compressed air; a piston operable by the compressed air to return the carriage to the right, a stop cock governing the admission of the compressed air into the cylinder, tabulating means for releasing the carriage to permit its motion and for stopping it at a predetermined point, a set of keys 70 operating the tabulating means but not operating the cock, and another set of tabulator keys operating both the tabulating means and the cock.

11. In a tabulating machine, a carriage, a tabulator bar mounted upon said carriage, a stop mounted upon said bar, means normally tending to move the carriage to the left, a series of tabulator rods each of which is 75 operative to release said carriage to permit its motion and then to stop the carriage by contacting with the tabulator stop, a returning bar operating a compressed air mechanism to return the carriage to the 80 right, a series of tabulator keys each of which operates its tabulator rod but does not operate the returning bar, and another set of tabulator keys each of which operates its tabulator rod and also the returning bar.

12. In a tabulating machine the combination of a carriage mechanism for advancing said carriage, mechanism to return said carriage, tabulating means, a set of keys operative on said tabulating means and said carriage advancing mechanism, and a second set of keys operative on said carriage returning mechanism and said tabulating mechanism.

13. In a tabulating machine: spring-driven mechanism for advancing the carriage; pneumatic mechanism for returning the carriage; means for stopping the carriage at a predetermined place; a set of advancing tabulating keys each of which controls the operation of both said spring-driven advancing mechanism and carriage-stopping means; and a set of returning tabulating keys controlling the operation of both the pneumatic returning mechanism and the carriage-stopping means.

14. In a tabulating machine: spring-driven mechanism for advancing the carriage; other mechanism for returning the carriage; means for stopping the carriage at a predetermined place; a set of advancing tabulating keys each of which controls the operation of both said spring-driven advancing mechanism and carriage-stopping means; and a set of returning tabulating keys controlling the operation of both the 120 returning mechanism and the carriage-stopping means.

15. In a tabulating machine the combination of a carriage, tabulating means, means to advance said carriage, a set of keys op- 130

erative on said tabulating means and said advancing means, the actuation of any one of said keys serving first to release said carriage and stop said carriage at a point determined by said tabulating means, means to return said carriage, and a second set of keys operative on said carriage returning means and tabulating means, the operation of any key of said second set serving to

return the said carriage and stop it at a point determined by said tabulating means.

In witness whereof, I have hereunto subscribed my name in the presence of two witnesses.

BESTER R. WEBSTER.
